(57) **CLAIM**

The ornamental design for a fastener, as shown and described.

DESCRIPTION

FIG. 1 is a front elevation view of a fastener.

FIG. 2 is a back elevation view of the fastener thereof.

FIG. 3 is a side elevation view of the fastener thereof.

FIG. 4 is an opposed side elevation view of the fastener thereof.

FIG. 5 is a top plan view of the fastener thereof; and,
FIG. 6 is a bottom plan view of the fastener thereof.

The broken line circles of FIGS. 1 and 2 and the broken line
threading are included for the purpose of showing portions of
the article and forms no part of the claimed design.
